UNITED STATES PATENT OFFICE.

GEORGE P. CARTER, OF FAIRFIELD, NORTH CAROLINA.

CHALK-LINE MARKER.

1,168,851.

Specification of Letters Patent. Patented Jan. 18, 1916.

Application filed March 6, 1915. Serial No. 12,617.

To all whom it may concern:

Be it known that I, GEORGE P. CARTER, a citizen of the United States, residing at 5 Fairfield, in the county of Hyde and State of North Carolina, have invented certain new and useful Improvements in Chalk-Line Markers, of which the following is a specification, reference being had to the accompanying drawings.

This invention relates to chalk line markers and has for its primary object to provide a simply constructed, serviceable device of this character for marking a guide line upon billiard tables, floors, or in other instances where it is necessary or desirable to provide a suitable guiding line or mark.

The invention has for a further object to provide a device of the above character including a drum having a line wound thereon, spring pressed chalking blocks, said line extending through a suitable guide and engaging said blocks at their opposed faces, rotatably mounted cylinders to contain the chalking blocks, and gearing connecting the drum shaft to one of the cylinder shafts whereby the chalking blocks are positively rotated as the line is unwound from the drum.

It is an additional object of my invention 30 to provide a chalk line marker which is so constructed as to reduce to a minimum, waste of the chalk, the holding cylinders for the chalk being removable so that the supply of chalk may be readily replenished and the 35 device, as a whole, being capable of manufacture at comparatively small cost.

With the above and other objects in view, my invention consists in the novel features of construction, combination, and arrangement of parts to be hereinafter more fully 40 described, claimed, and illustrated in the accompanying drawing, in which—

Figure 1 is a vertical section of my improved chalk line marker; Fig. 2 is a section 45 taken on the line 2—2 of Fig. 1; and Fig. 3 is a section taken on the line 3—3 of Fig. 1.

Referring in detail to the drawing, 5 50 designates the casing which is provided on its end walls with suitable bearings or supports for a longitudinally disposed shaft 6. Upon this shaft, the drum 7 is fixed, and to the same, one end of a flexible line 8 is suitably attached. A relatively short shaft 6' is also journaled in one end of the case and upon the same a gear wheel 9 is fixed, said gear wheel meshing with a pinion 9' secured

upon the shaft 6 so that said shaft will be driven at a relatively high speed. One end of a spiral spring 6^a is also fixed to the shaft 6', the other end thereof being suitably secured to the wall of the casing 5. The large gear wheel 10 is also fixed upon the shaft 6. A second longitudinally extending shaft 11 is mounted in suitable bearings 12 within the casing in axial alinement with the shaft 11 and upon the opposed ends of the shafts 11 and 13, the cylinders 14 are engaged and removably secured by means of suitable set screws indicated at 15.

C designates a plurality of chalk blocks or disks which are arranged in each of the cylinders 14 and normally forced outwardly by means of coil springs 16 in the inner ends of said cylinders. These springs yieldingly hold the outermost chalk disks in contact 75 with each other. The casing is preferably provided with a suitable compartment 17 to receive a supply of the chalk disks, said compartment having a door 18. A second door 19 is also provided in the front of the 80 case, whereby access may be had to the interior thereof for the purpose of removing the cylinders 14 from the respective shafts 11 and 13. Upon the shaft 11, a pinion 21 is fixed, with which the gear 10 meshes, 85 whereby said shaft 11 is positively driven.

In the operation of the device, when it is desired to mark a chalk line upon the table or other surface, the end of the cord or other flexible element 8, which extends through an opening in one wall of the case 5, is grasped and said cord pulled or unwound upon the drum 7. The shaft 6 is thus rotated and the spring 9 placed under tension. As the cord is withdrawn from the case, the same bears 90 against the outermost chalk disks in the cylinders 14 at the contacting faces thereof, and by such abrasive contact of the cord with the chalk, the cord becomes coated with the chalk powder. The chalk containing cylinders are so located with respect to the drum that there will be sufficient pressure of the line upon the chalk to insure the proper chalking of the line, but at the same time, avoid undue waste of the chalk. The ratio 95 between the gears is substantially such that for every revolution of the shaft 6', the shaft 6 carrying the spool or drum, makes 10 revolutions. It is, however, obvious that other ratios used may be provided, if desired, 110 to obtain an increase or decrease in speed of the spool shaft. By the provision of the

separate shafts 6 and 6', I may employ a relatively short spiral spring 6^a with a cord or line of maximum length.

From the foregoing description, taken in connection with the accompanying drawing, it will be seen that I have produced a very serviceable and reliable device for providing chalk guide lines. The cylinders 14 may be readily removed from the shafts 11 and 13 and replenished with chalk disks from the compartment 17. When the guide line is released, the spring 6^a will, of course, expand and rewind the line upon the drum 7. This line may be of any desired length, in accordance with the purpose for which the device is to be used. It is, of course, obvious that, if desired, friction wheels may be substituted for the gear 10 and pinion 21.

The device is also susceptible of considerable modification in the form, proportion, and arrangement of the several elements employed, and it will, therefore, be understood that I reserve the privilege of resorting to all such legitimate changes as may be fairly embodied within the spirit and scope of the invention as claimed.

Having thus fully described my invention, what I desire to claim and secure by Letters Patent is:—

30 1. A chalk line marker including a spring held drum, a line wound upon said drum, spaced axially alined shafts, cylinders fixed on said shafts, spring pressed chalk disks in

said cylinders, means for guiding said line in contact with the chalk disks, and gearing connecting the drum shaft to one of said latter shafts, whereby the chalk containing cylinders are positively rotated as the line is unwound from the drum. 35

2. A chalk marker including a casing, a shaft mounted in said casing, a drum fixed upon said line and a line wound upon said drum, a second shaft in the casing, a pinion fixed upon the first named shaft, a relatively large gear on the second shaft meshing with 40 said pinion, a spiral spring fixed to the case at one end and connected to the second shaft at its other end to rotate the same in one direction, a pair of spaced axially alined shafts mounted in said casing, cylinders removably 45 secured upon the opposed ends of said shaft, spring pressed chalk disks arranged in each of the cylinders, said line being adapted for passing between the outermost chalk disks, and gearing connecting one of the latter 50 shafts with the drum shaft whereby the chalk cylinders are rotated as the line is unwound from the drum, said spiral spring being simultaneously placed under tension. 55

In testimony whereof I hereunto affix my 60 signature in the presence of two witnesses.

GEORGE P. CARTER.
